Patented Apr. 25, 1922.

UNITED STATES PATENT OFFICE.

WILLIAM HARPER, JR., OF NEW YORK, N. Y., ASSIGNOR, BY MESNE ASSIGNMENTS, TO SKYRING AIRCRAFT CORPORATION, OF NEW YORK, N. Y., A CORPORATION OF NEW YORK.

COMBUSTION ENGINE.

1,413,912.

Specification of Letters Patent. Patented Apr. 25, 1922.

Application filed June 8, 1918. Serial No. 238,971.

To all whom it may concern:

Be it known that I, WILLIAM HARPER, Jr., a citizen of the United States, and a resident of New York city, in the county of New York and State of New York, have invented certain new and useful Improvements in Combustion Engines, of which the following is a specification.

This invention relates to combustion engines and has particular reference to improvements in aviation engines of the rotary cylinder type.

An object of this invention is to improve the construction of such engines in such manner as to reduce the waste of lubricating oil which occurs at present. The common practice now is to spray the lubricating oil into the incoming charge, which mixture passes directly from the bottom of the cylinder into the explosion space through a valve in the piston head. The result is that most of the oil passes directly through the valve at a high velocity due to the velocity of the charge plus the centrifugal velocity of the relatively heavier particles of oil mixed in the charge, the oil particles on account of their greater gravity having greater centrifugal velocity and tending to follow the shortest and most direct path, which is axially of the cylinder and straight through the central piston head valve. By this invention, I provide a tortuous path for the combined oil spray and gaseous charge mixture, preferably adjacent the circumference of the cylinder and within the trunk of the piston toward the head, the head being provided with a depending baffle around which the charge must pass in order to reach and pass through the central inlet valve to the firing chamber. It results from this that the relatively heavy oil particles whether of lubricating oil or ungasified fuel are largely retained by the cylinder head and baffle surface, without being wasted through the valve, the condensed oil then feeding by capillary attraction and centrifugal force through oil holes in the trunk of the piston to the cylinder bearing surface. This separation is aided by the difference in velocity or relatively heavy oil particles, and relatively light vapor or gas, the latter more easily passing around the baffle, while the former are trapped by the piston head and coalesce into liquids, unless vaporized by the piston heat. Any ungasified fuel which is

caught in this manner is partially or wholly cracked or gasified by the heat of the piston, and consumed in the cylinder.

A further feature of the invention resides in a positively actuated inlet valve mechanism applicable to existing engines without changing many parts, thereby rendering it possible to quickly convert engines already built, such for example as the well known "Gnome" engine to my improved engine. The piston head carries a valve support, valve, and valve rocker actuated by yielding means adjustably carried by the connecting rod so as to positively open the valve during the suction stroke but to yield so as to permit the valve to be held seated by cylinder pressure during the working stroke. The rocker is also counterbalanced so as to exert no lifting pressure on the valve by reason of centrifugal force, and the valve itself is also counterweighted for the same reason so as to hold it normally seated except when it is to be positively lifted. The parts of this invention, including the oil baffle, the valve and the wrist pin yoke are combined in a single unit which can be installed in present engines, it simply being necessary to take out the present valve mechanism and substitute mine, and to mount the yielding actuator on the present connecting rod, such conversion resulting in a decided oil and fuel economy, and large increase of power which is of great importance in view of the present scarcity of castor oil, and also in an increase of power and better fuel economy owing to better carburetion and positive valve action.

In the accompanying drawings,

Figure 1 is an elevation, and

Figure 2 is a bottom plan view of one piston.

1 is the rotary casing carrying air cooled cylinders 2, 3 the fixed hollow shaft having crank pin 4. 5 is the master-ring rotating on crank pin 4 and carrying the rigid connecting rod 6 connected to the piston 7 in the upper cylinder 2. The other pistons 7 are connected to the master-ring 5 by pivoted connecting rods 8 in the usual manner. Each piston is also provided with the usual non-interference notch 9.

The trunk and head of the piston may be made in any desired manner but are shown in one piece, the head being open in the center to receive a webbed valve ring seat 12 having segmental gas ports and carrying 110

valve 13 with the usual stem 14. Threaded into the ring 12 is a ring 16 having a depending flange or skirt 17, which forms with the piston exterior thereof, the oil spray baffling chamber, as will be hereinafter explained. The ring 16 also carries heavy depending lugs 18 forming a yoke and bored to receive the wrist pin 19, the wrist pin being secured in the usual manner. The lugs 18 are connected by curved reinforcing webs 20, so formed as to provide the gas passages 21 within the skirt 17 and giving free and ample passage area through the valve 13 from the crank case. The valve stem bushing 22 is threaded into the lug 23 carried by the valve seat ring 12, and the bushing 22 carries depending ears 24 in which are pivoted the valve stem counterweight levers 25, pivoting being effected by a U-shaped pin 26, and the inner ends of the counterweight levers projecting into a slot 27 in the valve stem 14. The valve is normally held seated under slight pressure by means of a double coil spring 28, which engages the arms 29 on the counterweight levers 25. The spring 28 acting through the levers 25 holds the valve seated when the engine is at rest with the valve in normal seated position, and when the engine is operating, the weights 25 slightly overbalance the centrifugal force of the valve itself and hold it seated, so that centrifugal force is not relied upon in any respect to open the valve in this engine.

30 is the valve rocker pivoted at 31 in extensions 32 on the skirt 17, and having the counterweight 33. When the valve is seated, the end of the lever 30 rests between the end of the valve stem and the wrist pin 26, 10 the upper end of the connecting rod being slotted through a sufficient arc 34 to permit this. To operate the rocker 30, a stiff double spring actuator 36 is provided, which straddles the valve stem and the rocker and passes 15 under the rocker and is adjustably connected at its lower end 37 by bolt 38 and notched clamp washers 39 to the master-rod 6, and likewise in the other cylinders, to the respective connecting rods 8. Pins 35 hold the 20 end of the actuator 36 when not flexed, so as to damp it and prevent vibration of the end under the high engine speed.

When the valve is seated, with the piston at its extreme upward position, the yielding rocker actuator 36 is not under any stress but as the piston moves down in the cylinder owing to rotation of the cylinder to the left of the crank pin 4, the actuator 36 lifts the rocker 30 and imparts to the valve a multiplied movement, causing the valve to open if the cylinder is working on the suction stroke. During the working stroke, the cylinder pressure holds the valve seated against the lifting force of the yielding actuator 36, 65 as seen in the intermediate cylinder shown

on the drawing, which is part way through the working stroke. The exhaust occurs during the outward stroke while the actuator 36 is out of contact with the rocker 30. The actuator 36 is adjustable vertically in 70 the clamping device so as to change the timing, it being seen that by adjusting the actuator upward the valve opens sooner than when it is adjusted so as to bring the part which engages with the rocker 30 slightly 75 out of contact therewith. Also the actuator can readily be bent to change the leverage or timing, if desired, and still hold it normally engaged with pin 35.

Within the piston is a dished plate 40 having ports 41 adjacent its periphery, for deflecting the fuel and oil spray outwardly, this plate being seated in the piston and held by an expanding spring ring 42, the ports 41 being above the bottom of the skirt 17, 85 so that the mixture of firing charge and lubricating oil spray first strikes plate 40 and drops considerable oil, and then passes upwardly through the ports 41 and is again deflected around the lower edge of the skirt 17 90 before passing upwardly to and through the valve. The oil spray particles being heavier than the firing charge and having greater centrifugal velocity condense on these surfaces and run through lubricating holes 44 in 95 the piston to the cylinder surface. The ports 41 are triangular, and have raised rims on the inner side, so as to prevent drops of oil forming on the edges of the ports and being drawn through.

To increase the rapidity of exhaust, each cylinder is provided with a curved deflecting hood 47 which deflects the air across the exhaust port 48 and out at 49, 50 being the exhaust valve located to be cooled by the blast 105 across the top and preferably actuated by the mechanism described in my aforesaid application.

It will be seen that by these improvements, the oil spray will largely condense on the 110 piston, baffle, and plate 40, feeding thence by capillary attraction and centrifugal force to the cylinder surface, although sufficient oil will be carried around by the charge to lubricate the valve parts. Not only does 115 this economize in expensive castor or other high grade oil, but better combustion is obtained with a cleaner engine. Although the baffling arrangement may be applied to present engines having suction actuated inlet 120 valves, a decided advantage is secured in combination with positive valve actuating means in elimination of valve sticking found in present engines, and increased power by reason of better carburetion, increased compression and certain and regular valve operation.

Another advantage of this invention is that the charge, largely freed of oil by the plate 40, becomes completely vaporized by 130

striking the hot piston, and also cools the piston, so that the formation of hot spots causing preignition is avoided. At the same time, the charge does not become heated to such extent as to reduce the volumetric efficiency, and carbon or tar does not tend to deposit in the piston corner since there is no dead space, the charge practically scavenging the entire interior of the piston. 10 Avoiding preignition, permits higher compression.

A further advantage of this invention is that the new parts can readily be added to existing engines as a complete unit, it only 15 being necessary to perform a few machining operations to the old parts, such as enlarging the hole in the piston, slotting the upper end of the connecting rod, then adding the valve ring seat and associated parts, and 20 clamping the actuator to the connecting rod in the proper position and applying the deflector plate. The connecting rod length remains the same, and the slight raising of the valve seat and valve above the piston 25 top has no objectionable effect.

Various changes and modifications may be made without departing from the scope of the appended claims.

What is claimed is:

30 1. In a combustion engine lubricated by oil spray mixed with the fuel charge and having an inlet valve in the piston, means comprising a baffle within the piston surrounding the entrance side of the valve and 35 a spaced plate for separating relatively heavy oil spray from relatively light gaseous fuel charge.

2. A combustion engine having a piston, an inlet valve therein, a deflecting plate below the valve, and a baffle between the plate 40 and the valve entrance.

3. A combustion engine having a piston, an inlet valve therein, a deflecting plate below the valve arranged to deflect the charge 45 in a radial direction, and a baffle arranged to prevent direct passage of the charge to the valve entrance.

4. A combustion engine having a piston, an inlet valve therein, and a deflecting plate below the valve arranged to deflect the charge 50 in a radial direction away from direct passage through the valve.

5. Means for converting suction operated inlet valves of a rotary cylinder engine into positively actuated valves protected 55 from excess supply of lubricating oil, comprising a valve seat, valve, rocker, connecting rod yoke and oil deflector adapted to be attached to the piston head, a rocker actuator adapted to be mounted on the connecting 60 rod, and a deflecting plate adapted to be mounted on the piston below said oil deflector.

6. A rotary cylinder combustion engine comprising a cylinder having a piston carrying an inlet valve for admitting charge from the crank case to the cylinder, and baffling means carried by the piston for directing the incoming charge against the piston head and then away therefrom before reaching 70 the valve.

7. In a rotary cylinder combustion engine having yielding means for positively actuating a valve in the piston, means for damping vibration of said actuating means. 75

8. In a rotary cylinder combustion engine having an inlet valve in the piston, a yielding actuator for said valve mounted on the connecting rod, and means holding said actuator against vibration. 80

9. In a rotary cylinder combustion engine having a positively actuated inlet valve in the piston, baffling means carried by the piston comprising a transverse plate and a depending skirt for separating oil and pre-heating the fuel charge before reaching the valve. 85

Signed at New York city, in the county of New York and State of New York, this 6th day of June, A. D. 1918.

WILLIAM HARPER, JR.
